UNITED STATES PATENT OFFICE.

CONNIE H. EASTBURG, OF IDAHO FALLS, IDAHO.

SCYTHE.

1,218,535.

Specification of Letters Patent.

Patented Mar. 6, 1917.

Application filed April 21, 1915. Serial No. 22,936.

To all whom it may concern:

Be it known that I, CONNIE H. EASTBURG, a citizen of the United States, residing at Idaho Falls, in the county of Bonneville 5 and State of Idaho, have invented certain new and useful Improvements in Scythes, of which the following is a specification.

This invention has reference to scythes and the like, and has for an object to provide a device of this character wherein novel means are employed for adjustably securing the scythe blade to the snath.

Another object consists in the provision of means for bracing the scythe snath, said 15 means being formed integral with the scythe blade and adapted to adjustably connect the blade to the snath, the snath being further provided with means for engaging and holding the scythe blade in its adjusted position.

With the foregoing and other objects in view, my invention consists in such details of construction and arrangement and combination of parts as will be hereinafter more fully described and pointed out in the appended claims.

In describing my invention in detail, reference will be had to the accompanying drawings, wherein:

Figure 1 is a view in side elevation of a 30 scythe, showing the application of my invention;

Fig. 2 is a sectional view taken on the line 2-2 of Fig. 1;

Fig. 3 is a view in perspective of the 35 housing or sleeve member carried by the scythe snath; and

Fig. 4 is a fragmentary view of the scythe blade, showing the connection and bracing means therefor.

Referring to the drawings:—

Numeral 1 designates a scythe snath which has its lower extremity reduced to provide a substantially rectangular portion 2. A housing or sleeve member, which in 45 the present instance comprises front and rear walls 3, and side walls 4 and 5 respectively, is adapted to snugly engage the reduced portion 2 of the snath and is secured thereto by suitable fastening means 6, inserted through the openings 7 of the housing. The side wall 5 has a portion of its lateral edge continued to provide an extension 8 which has an opening 9 provided therein. The outer face of the extension is 50 further provided with corrugations, as indicated at 10, which extend completely

across the lower part of the wall 5 as shown to advantage in Fig. 3 of the drawings.

The scythe blade 11 which is adapted to be connected to both the snath 1 and the 60 housing 2, has its rear end bifurcated to provide a connecting arm or tang 12, and an upwardly curved bracing member 13. The connecting arm 12 extends rearwardly of and in symmetrical relation with the scythe 65 blade and has its inner face provided with corrugations, as indicated at 14. This corrugated arm 12 is adapted to engage the corrugated portion of the housing 3, when securing the scythe blade to the snath, and 70 is adjustably secured thereto by means of a bolt 16, working in the slot 15 of the connecting arm and passing through the opening 9 of the corrugated extension 8. Suitable tightening means 17 are provided upon 75 the bolt for clamping the corrugated faces 10 and 14 respectively in a locked position, thereby preventing the displacement of the scythe blade 11 from any adjusted position.

The bracing member 13 is formed integral 80 with the scythe blade 11 and is curved upwardly and rearwardly therefrom terminating in an enlarged head 18 which engages the scythe snath at an appreciable distance above the housing 3. An opening 19 is formed in 85 the enlarged head 18 and suitable fastening means are passed therethrough for pivotally securing the scythe blade to the snath as shown at 20. This member 13 provides a brace for the snath and prevents the breaking or snapping of the same, when mowing heavy weeds or bushes. A knife edge 21 is further provided upon this bracing member and forms a continuation of the cutting edge of the scythe blade, and greatly facilitates 95 the cutting or mowing operation of the scythe.

It will be understood that the above description and accompanying drawings comprehend only the general and preferred embodiment of my invention and that various minor changes in details of construction, proportion and arrangement of the parts may be made within the scope of the appended claims and without sacrificing any of 105 the advantages of my invention.

Having thus fully described my invention what I claim as new and desire to secure by Letters Patent is:—

1. The combination with a snath and a 110 housing carried by said snath, of a scythe blade having its rear end bifurcated, one of

said bifurcations forming the connecting tang for said blade and extending rearwardly of the scythe blade proper, the other of said bifurcations curved upwardly 5 from said slotted tang member and at a point adjacent the cutting edge of the blade, to provide bracing means therefor, said upwardly curved member having a sharpened edge forming a continuation of the cutting 10 edge of the scythe blade, the free end of said bracing member being provided with an enlarged head for pivotal engagement with the scythe snath.

2. A scythe, including a snath having a 15 reduced end portion, a tubular sleeve member fitted upon said reduced end and provided with a corrugated extension at its lowermost end, said corrugations continued to extend from said extension clear across 20 the lower portion of said sleeve, a scythe blade, said blade having its rear end bifurcated to provide divergent arms, one of said arms being slotted and corrugated for engagement with the corrugations of said 25 sleeve, the other arm being adapted to extend upwardly into engagement with said snath and pivoted thereto, said latter arm issuing into, and forming a continuation of, the cutting edge of said blade, and locking 30 means carried by said extension and working in the slot of said first mentioned arm,

whereby said blade may be locked in its adjusted position.

3. A scythe including a snath having its lowermost portion incased within the walls 35 of a box-like housing, one side of which is partially extended to project forwardly of the snath and housing, a scythe blade having a slotted rear end for engagement with the projecting portion of the housing, one face 40 of said slotted end having teeth provided thereon, adjacent the sides of the slot and corresponding with similar teeth carried by the projecting portion of the housing, adjustable fastening means carried by said projecting portion and passing through said slotted end, for securing the latter to the 45 projecting portion, and bracing formed integral with said blade and extending upwardly and rearwardly above the slotted end 50 of the blade and pivotally connecting said blade to said snath, said bracing means provided with a cutting edge issuing into the cutting edge proper of the scythe blade and forming a continuation thereof, as and for 55 the purpose specified.

In testimony whereof I affix my signature in presence of two witnesses.

CONNIE H. EASTBURG.
